UNITED STATES PATENT OFFICE.

ROBERT FRIEDRICH, OF PHILADELPHIA, PENNSYLVANIA.

DESIGN FOR HOSIERY.

Application filed December 9, 1927. Serial No. 24,427. Term of patent 14 years.

To all whom it may concern:

Be it known that I, ROBERT FRIEDRICH, a citizen of the United States, residing at Philadelphia, in the county of Philadelphia and State of Pennsylvania, have invented a new, original, and ornamental Design for Hosiery, of which the following is a specification, reference being had to the accompanying drawing, forming a part thereof.

The figure is an end elevation of the stocking showing my new design, the upper part being broken away.

I claim:

The ornamental design for hosiery, as shown.

ROBERT FRIEDRICH.
